United States Patent Office

Des. 198,431
Patented June 16, 1964

198,431

WATER CLOSET

William H. Armstrong, Birmingham, Mich., assignor to
Borg-Warner Corporation, a corporation of Illinois

Filed Oct. 10, 1962, Ser. No. 72,056

Term of patent 14 years

(Cl. D4—5)

Fig. 2

Fig. 3

Fig. 4

Fig. 5

FIG. 1 is a front perspective view taken from one side of a water closet showing my new design;

FIG. 2 is a top plan view thereof;

FIG. 3 is a front elevational view thereof;

FIG. 4 is a rear elevational view thereof; and

FIG. 5 is an elevational view taken from the side opposite that shown in FIG. 1.

I claim:

The ornamental design for a water closet, substantially as shown.
